UNITED STATES PATENT OFFICE.

WILLIAM H. BLEUEL, OF PITTSBURGH, PENNSYLVANIA.

AUTOMATIC SPRING MACHINE.

Application filed September 23, 1922. Serial No. 589,989.

To all whom it may concern:

Be it known that I, WILLIAM H. BLEUEL, a citizen of the United States, and residing in the city of Pittsburgh, in the county of Allegheny and State of Pennsylvania, have invented or discovered the new, useful, and Improved Automatic Spring Machine, of which the following is a specification.

My invention consists in certain new and useful improvements in automatic spring machines.

More particularly my invention is characterized, inter alia, by the following novel and advantageous features.

I show a novel combination of structural elements and operative parts which coact to form a simplified and greatly improved machine which is readily adjustable to form spring from wire or rods of any diameter and cross section, and spread of spirals, and either of cylindrical, tapered or partially cylindrical and partially tapered form.

I show a new and improved chain feed for the material from which the springs are formed.

I show a new and improved adjustable forming means whereby the diameter and character of the spring is determined.

I show new and improved means for severing the formed spring, said means being operated by stored power instead of directly from a power-driven element of the machine.

I show new and improved means for spacing apart the coils of the springs, said means being adjustable, so that tightly coiled or open spirals may be formed.

Many other novel features of construction and arrangement of parts will appear from the following description.

In the accompanying drawings, which are, however, merely intended to illustrate the principles of my invention without limiting the scope of the latter to the construction shown, Figure 1 is a broken front elevation of an automatic spring machine embodying said principles; Fig. 2 is a side view of the same, showing the wire feed, the spring forming and the spring cutting means, the latter being shown in its inoperative position; Fig. 3 is a view of the opposite side of the machine; Fig. 4 is a broken section of the machine taken at right angles to Figs. 2 and 3; Fig. 5 is a detail of the guide through which the material is fed to the

forming means; Fig. 6 is a section taken along the line VI—VI in Fig. 5; Fig. 7 is a detail showing the cam and roller mechanism which operates the spreader; Fig. 8 is a detail view showing the mechanism used to move the former in tapering a spring while the same is being wound around the mandrel; Fig. 9 is an enlarged detail showing the adjustment of the former, and Fig. 10 is another view of the same, taken at right angles to Fig. 9; Figs. 11, 12, and 13 are details showing the blocks which make up the chain feed. Fig. 14 is a top plan view of the cutter head and the cutter mounted thereon; Fig. 15 is a side view of the same, showing the cutter in its cutting position, the spreader being also shown; Fig. 16 is an enlarged detail in section showing the control of the spreader and former; and Fig. 17 is a detail view showing the upper chain supporting plate in end elevation, the chain being omitted.

The following is a detailed description of the drawings:

The frame of the machine is formed by the side plates A and B supported on legs 1 and rigidly connected in spaced relation by the spreaders 2.

3 and 4 represent the variable speed drive shafts provided with the usual pulley 5 and gears 6, the shaft 4 being journaled in the bearing boxes 7 eccentrically mounted in suitable bearings 8 in the upper portions of the side plates A and B.

9 is the power delivery gear on the shaft 4.

I will first describe the means for feeding the wire or rod, from which the springs are to be made, to the forming and cutting mechanism.

10 represents a spur shaft mounted on the inner side of the side plate B and upon which is rotatably mounted the gear 11 which meshes with the gear 9, and also meshed from above with the horizontally aligned gears 12 and 13 keyed, respectively, on the shafts 14 and 15 which are journaled in suitable roller bearings in the side plates A and B. 16 and 17 are a pair of horizontally aligned shafts, one vertically aligned with each of the shafts 14 and 15, and journaled in suitable bearings in the plates A and B. 18 and 19 are gears keyed, respectively, on the shafts 16 and 17, and in mesh with the gears 12 and 13, respectively,

whereby the shafts 16 and 17 are driven in the opposite direction to shafts 14 and 15.

Roller bearings 20 mounted in suitable boxes are preferably provided for the shafts. 5 Said shafts protrude through the side plate A and have keyed on their protruding ends pairs of spaced-apart sprockets. Thus the shaft 14 is provided with the sprockets 21; the shaft 15 with the sprockets 22; the 10 shaft 16 with sprockets 23, and the shaft 17 with the sprockets 24.

25 is a horizontally disposed chain supporting plate having its ends provided with vertically slotted holes 26 by means of which 15 it may be mounted on the shafts 14 and 17 between the members of the pairs of sprockets, said plate being capable of vertical movement relative to the shafts owing to the slotted nature of said holes 26. Similarly 20 the plate 27 is mounted on the shafts 16 and 17. The plate 25 is provided with a rearwardly extending bracket 29 which bears against the side plate A and is provided with a pair of downwardly extending sockets 30 to receive the lower ends of the adjustment bolts 31 screwed down through threaded holes in the bracket 32 extending from the side plate A. Similarly the plate 27 is provided with a rearwardly extending 25 bracket having upwardly extending sockets to receive the ends of the adjustment bolts 33 screwed up through threaded holes in the bracket 34 extending from the side plate A. It is evident that by means of the adjustment bolts the plates 25 and 27 may be 30 moved toward or away from each other. The plates may be clamped in any adjusted position by means of screws 35 extending through vertically slotted holes 36 in the 35 intermediate portions of said plates, and screwed into threaded holes in the side plate A.

The four sprockets 21-21 and 22-22 carry the upper chain, while the four 45 sprockets 23-23 and 24-24 carry the lower chain, the upper sprockets moving clockwise and the lower sprockets counterclockwise in Fig. 2.

The chains are each composed of a series 50 of blocks 37 pivotally connected together at their ends by pivot pins which are engaged by the teeth of the sprockets. Thus one end of each block is provided with a pair of parallel, spaced apart and pierced ears 38 while 55 the opposite end is provided with a central pierced ear 38^a which is inserted between the ears 38 on the end of the adjacent block and pivot pin 39 inserted through the same. 40 represents rollers mounted on said pins 60 on either side of the blocks, which rollers are engaged by the teeth of the sprockets to drive the chains. The outer ends of the pins are connected by links 41, and 42 are caps 65 screwed onto the ends of the pins to keep the same in position. The perimeters of the

plates 25 and 27 conform to the path of travel of the chains and are provided with a continuous groove, preferably rectangular in which are mounted the roller bearings 43, against which bearings the butts of the 70 blocks 36 bear, thus keeping the blocks in proper alignment during their travel. The outer face of each block is provided with a plurality of projecting teeth 44 which are in staggered relation to each other on either 75 side of the medial line of said block and are provided with curved wire engaging faces. Thus the teeth of the blocks of the lower flight of the upper chain interface with the teeth of the blocks of the upper flight of the 80 lower chain, thereby gripping between them the wire or rod which is being fed forward to the forming and cutting mechanism.

By adjusting the plates 25 and 27 toward or away from each other the grip may be 85 regulated to properly fit the diameter of wire or rod to be fed, and the roller support of the chain blocks renders the grip of the chains on the material continuous for the full length of the feed. The feeding mechanism therefore provides a positive and uniform feed which does not require so tight a grip on the material, as to crush or distort the cross section of the same. I may therefore 90 use wire or rod of any desired cross sectional shape in my machine without danger of crushing or distorting the same.

I provide suitable means for directing the wire or rod between the chains, and the same is shown as of the following construction. 100

45 is a guide block provided with a diametric passage 46 for the wire or rod. The guide block is supported in place by the insertion of its shank in a socket hole in the plate A. 105

The material is fed forward from the chain feeding mechanism through an adjustable guide of the following construction. 51 represents a pair of blocks fitting together longitudinally and one of said blocks 110 being provided on its inner face with a groove of proper size to admit the rod or wire. Said blocks are seated between the upper and lower horizontal flanges 52 of a holder 53 which is pivotally mounted on the 115 sideplate A, as by means of a bolt 54 so positioned that the axis of pivotal swing of the blocks 51 is aligned with the axis of the chain feed. The blocks are held in place by means of the face plate 55 having slotted 120 ends by means of which it is clamped to the face plate A, by tightening the bolts 56. 57 is a set screw extending through a threaded hole in the face plate and impinging against the front block 51, thereby holding the 125 blocks rigidly in the holder. The guide is held down in its desired position by means of a limit screw 58 depending through a threaded hole in a projection 59 on the side-plate A. 130

60 is the mandrel about which the wire or other material is wound to form the spring. Said mandrel is of semi-circular form, the underside being cut away, and 5 is provided with a squared shank by means of which it is mounted in a suitable socket in the side plate A.

The advancing material is directed down around the mandrel by the former which 10 consists of a tool 61 having a concaved engaging surface 62 against which the material impinges and which turns the same down around the mandrel. The tool 61 is removably mounted in a seat on the vertical face of a holder block 63, a bolted-on wedge plate 64 being used to clamp said tool into engagement with an undercut flange 65 on the holder. 66 is a depending set screw carried by the holder and 20 impinging against the upper end of the tool for the purpose of adjusting the position of the tool in relation to the holder.

The holder 63 is rigidly mounted on the projecting end of a shaft 67 journaled 25 in the sideplates A and B. Inside the plate A said shaft is provided with a rigidly attached radial arm 68 whose outer end is provided with a threaded split socket 69 in which is screwed the screw shaft 70 provided at its upper end with the hand wheel 71. 72 is the bolt used to clamp said sockets about said screw to hold the latter stationary relative to the socket. The lower end of said screw 70 impinges against a 35 stop block 73 extending from the inner face of plate A. Thus by means of the screw 70 the former may be moved toward or away from the mandrel, thus adjusting the diameter of the springs formed.

40 The shaft 67 is made extensible so that the former may be moved into proper position to engage and bend the wire. Thus the left end of the shaft 67 is provided with a threaded portion which extends through the orifice of a supporting plate 74 spaced inwardly from the side plate B and on either side of said supporting plate are adjustment nuts 75 by means of which the shaft 67 may be shifted longitudinally. The 45 end of the shaft 67 is reduced and occupies a bearing 76 in the plate B.

Where cylindrical or constant diameter springs are to be made, the former is first 50 adjusted to proper position and then remains untouched until the job is finished. Where, on the contrary, tapered springs are to be made, provision must be made for varying the position of the former relative to the mandrel during the operation of coiling the spring.

For this purpose I show provided a radial arm 77 fixed on the shaft 67 and provided at its end with a roller 78 which impinges on the perimeter of a cam 79 mounted on a driven shaft 80 journaled in the

side plates A and B. It is evident that in following the perimetral contour of the cam 79, the roller 78 will cause the shaft 67 to turn, thereby moving the former toward or away from the mandrel, in accordance with the contour of the cam, and thus progressively increasing or reducing the diameter of the spring and thereby obtaining the desired taper.

I will next describe the spreader by means 75 of which the snugness of the coils is determined.

The spreader consists of a bevelled edge tool 81 mounted in a seat 82 in a holder block 83 by means of set screws 84, and 80 extending up beneath the mandrel. The holder 83 is rigidly mounted on the protruding ends of the parallel rods 85 and 86 which are slidably mounted in bearings in the side plates A and B, so as to move 85 longitudinally to impart the necessary spreading movement to the tool 81. 87 is an arm rigidly secured to the said rods and having on its outer end a roller 88 adapted to contact with the surface of a cam mounted on the driven shaft 80. For convenience I prefer to use the face of the cam 79 above referred to, giving the right hand face of said cam the irregular surface necessary to produce the desired movement of the 90 spreader. If desired the two cam functions may be performed by two separate cams mounted on the shaft 67, but I prefer to combine these functions in the same cam, using both the perimetral and facial surfaces of said cam for these purposes.

It is evident that where cylindrical springs are to be formed the perimetral contour of the cam 79 may be perfect circle.

105 The cam 79 may be clamped against a shoulder 89 on the shaft 80 by means of a sleeve nut 90 engaging a threaded portion of said shaft. Where the cam 79 is used simply to move the spreader, the cam may be cut away for a portion of its circumference, as shown in Fig. 7, so that it can be readily slipped laterally into position on the shaft and clamped in place.

110 The roller 88 is held in continuous contact with the face of cam 79 by means of a screw 91 mounted on a collar 92 slidably mounted on the rod 86 and forced away from the plate A by means of a helical spring 93 coiled about said rod.

115 The movement of the rods 85 and 86 toward the left in Fig. 4 may be adjusted by means of the bearing sleeve 94 in which the end of the rod 85 is journaled, said sleeve being screwed into a threaded hole 120 in the plate B; while 95 is a collar pinned on the rod 86 and adapted to contact with the end of the sleeve 94. Thus by screwing the sleeve in or out, the proper limitation of movement toward the left in Fig.

125 130

4 may be obtained on the rods 85 and 86

I will next describe the mechanism for cutting off the completed spring.

96 is the cutting tool provided with a sharp edge and clamped as by set screw 97 in the seat 98 of the plate 99 which is pivotally mounted as by the pivot pin 100 on the top surface of the head 101. The tool 96 is held down in its seat by the small plate 99^a bolted to the plate 99. A cotter pin 100^a holds the pin 100 in its socket in head 101. The front edge of the plate 99 is provided with a downwardly extending arcuate flange 102 which engages a similar recess in the front of the head 101, said flange and recess being concentric with the pivot of the plate. Said plate is also provided with a downwardly extending projection 103 which travels in an arcuate groove in the top surface of said head, and at the inner end of said groove is provided a socket or seat 104 for a spring 105 which tends to force the plate to swing clockwise in relation to the head, the movement of said plate being however limited by a stop plate 106 carried by the head. 107 is a set screw carried by the plate 99 for adjusting the projection of the tool relative to said plate.

30 The head 101 is integral with the upper end of a lever 108 whose lower end is provided with a collar 109 keyed on the projecting end of a shaft 110 journaled in the side plates A and B. Inside the sideplate

35 B the shaft 110 is provided with a bifurcated toe-piece 111 which extends on either side of the spring rod 112 to bear on the top of the cap 113 sliding on said spring rod and bearing on the upper end of a strong 40 helical spring 114 coiled about said rod between said cap and a cap 115 fixed on the lower end of said rod. The said rod extends up through a nut block 116 carried by the plate B, said rod being threaded to screw 45 in said block for adjustment of the compression of the spring 114, a lock sleeve 117 being screwed on said rod above said nut block to lock said rod in any adjusted position. 118 is a hand wheel on the upper end 50 of said spring rod. It is evident that the effect of the expansion of the spring 114 is to throw the cutting tool into its cutting position, as shown in Fig. 14 for the cutting operation, and the spring 114 is accordingly 55 compressed to store power for the next cutting operation, by means of the cam 119 mounted on the driven shaft 80 and engaging an angular projection 120 on the cutter lever 108. The cam is provided with a spiral perimetral cam surface 121 interrupted by a radial shoulder 122, so that the cutter will 60 be gradually retracted and power gradually stored in the spring, until the cam rotates into the position in which the projection 65 travels off the high point of the cam when

the cutter will be thrown forward, into the position shown in Fig. 15, by the sudden expansion of the spring. A resilient bumper 123 carried by the plate A will halt the forward throw of the cutter, after the spring 70 has been severed, without a jar on the machine. The continued rotation of the cam will gradually retract the cutter and compress the spring to store up power for the next cutting operation. 75

The shaft 80, which, as has been seen, controls the operation of the cutter, the spreader and the former, is shown power-driven in the following manner.

Said shaft is prolonged through its bearing in the side plate B as is also the sprocket shaft 17, and mounted on the protruding portions of said shafts, as by sleeve bearings, is the saddle 124 whose upper portion is provided with an arcuate slot 125 concentric 85 with the shaft 80. A gear 126 is keyed on the end of the shaft 80 and an idler pinion 127 is rotatably mounted on a stud shaft 128 which is clamped in the slot 125 in any adjusted position, said pinion however being 90 always in mesh with the gear 126. 129 is a gear keyed on the end of the shaft 17 and in mesh with the pinion 127 so that power is thus applied to the shaft 80. It is evident 95 that the speed of the shaft 80 may be regulated by using a larger or smaller gear on the end of the shaft 17, the pinion 127 being shifted along the slot 125 to mesh with the two gears.

The operation of my machine is as 100 follows:—

The wire or rod, from which the springs are to be made, is introduced through the block 45 between the chains which feed the material forward through the guide blocks 105 to the mandrel, about which it is coiled by the former, the spreader, as it moves out, spreading the coils to the desired degree. When the proper length of spring has been formed, the cutter is thrown forward by 110 means of the stored power, severing the spring, and the cutter is then again retracted by its cam, recompressing the spring to store power for the next cutting operation. 115

The severed end of wire, as it is fed forward immediately after the cut, shoulders the cutting tool 96 out of the way, swinging the plate 99 on its axis and compressing the spring 105. As the cutter is drawn back by the cam 119, the spring 105 swings the plate 99 and the cutter 96 back into its normal position relative to the head 101. 120

It is evident that the speed of the shaft 80 determines the length of the spring which is made, since the cutting operation occurs once in every revolution of the cam 119. Therefore by selecting the gear 129 of the proper size for the end of shaft 17, and thus adjusting the speed of the shaft 80, I am able to produce springs of any desired length. 125 130

The diameter of the spring formed is determined by the position of the former 61, which, when a cylindrical spring is to be formed, may be regulated by means of the screw shaft 70, the former being adjusted farther away from the mandrel to produce a spring of larger diameter. The spread of the coils of the springs is regulated by movement of the spreader 81, and said movement is of course controlled by the contour of the face of the cam 79, so that either loosely or tightly coiled springs may be produced.

Where tapered springs are to be formed I retract the screw shaft 70 so that it is out of contact of the block 73 and cause the former to progressively advance toward or move away from the mandrel by means of the roller 78 on the perimeter of the cam 79. Thus the cam 79 is used to determine both the 20 taper and the spread of the spring.

It is evident, therefore, that by providing the proper gear 129 and the proper cam 79 the machine may be quickly set to produce a spring of any desired character. Thus by 25 properly marking the proper gear and cam and giving the same marking to the order, I can set the machine up for a repeat order in a very few minutes.

It is also evident that by properly adjusting the chain supporting plates 25 and 27, any gauge or character of material may be fed to the mandrel. The chain feed maintains a more extended grip on the material than roll feed and therefore does not require 30 to grip the material with as much force. I thus avoid any danger of flattening or distorting the cross section of the material, as frequently happens where a roll feed is used. There is also no danger of the material slipping in the feed or being fed irregularly. I can also successfully feed material of 35 square or angular cross section without fear of distortion.

The use of stored power for the cutting 40 operation is a great advantage, owing to the fact that the machine is not jarred when the cutting operation occurs, as is the case where the cutter is operated by a cam driven directly from the machine.

50 Although, for the sake of clearness, I have minutely described the embodiment of the principles of my invention illustrated in the drawings, I do not wish to limit myself thereby, but claim broadly—

55 1. In a machine for the manufacture of springs, the combination of means for feeding the material, means for coiling the material, means whereby the operation of the machine stores power, means for releasing the power stored at predetermined intervals, means for regulating the amount of power stored, and means for severing the formed 60 springs from the material engaged by the feeding means actuated by the release of said stored power.

2. In a machine for the manufacture of springs, the combination of a mandrel, means for continuously feeding the material to said mandrel, a former adapted to coil the material about said mandrel, means for adjusting the position of said former relative to said mandrel to determine the diameter of the springs to be formed, and a cutter arranged to strike against the wire on the mandrel for severing the completed springs at 75 the mandrel.

3. In a machine for the manufacture of springs, the combination of a mandrel, means for continuously feeding the material to said mandrel, a former adapted to coil 80 said material about said mandrel, a cutter arranged to strike against the wire on the mandrel for severing the completed springs at the mandrel, and means for varying the relation of said former to said mandrel to 85 vary the diameter of the springs formed.

4. In a machine for the manufacture of springs, the combination of a mandrel, means for continuously feeding the material to said mandrel, a former adapted to coil 90 said material about said mandrel, a cutter arranged to strike against the wire on the mandrel for severing the completed springs at the mandrel, and cam operated means for moving said former relative to said mandrel 95 for varying the diameter of the springs formed.

5. In a machine for the manufacture of springs, the combination of a mandrel, means for continuously feeding the material 100 about said mandrel, a former adapted to coil said material about said mandrel, means for severing the completed springs, a mounting for said former and pivotally mounted so as to swing in a plane at right angles to the axis of said mandrel, and cam means for 105 rocking said mounting to vary the diameter of the springs formed.

6. In a machine for the manufacture of springs, the combination of a mandrel, means for continuously feeding the material to said mandrel, a former adapted to coil 110 said material about said mandrel, a holder for said former and pivotally mounted to swing in a plane at right angles to the axis of the mandrel, means for severing the completed springs, a rotary shaft, and cam means carried by said shaft and adapted to move said holder whereby the diameter of 115 the spring formed may be varied.

7. In a machine for the manufacture of springs, the combination of a mandrel, means for continuously feeding the material to said mandrel, means for severing the completed springs, a spreader adapted to spread 120 the coils as they are formed on the mandrel, a rotary shaft, and cam means mounted on said shaft and operating said spreader.

8. In a machine for the manufacture of springs, the combination of a mandrel, 125

- means for continuously feeding the material to said mandrel, a former adapted to coil said material about said mandrel, means for severing the completed springs, a spreader 5 adapted to spread the coils as they are formed on said mandrel, a sliding mounting for said spreader, a rotary shaft, and cam means mounted on said shaft for moving said mounting to operate said spreader.
- 10 9. In a machine for the manufacture of springs, the combination of a mandrel, means for continuously feeding the material to said mandrel, a former adapted to coil said material about said mandrel, said former being movable relative to said mandrel to vary the diameter of the coils, a spreader movable in parallelism with said mandrel to spread the coils as they are formed, a rotary shaft, a removably mounted unit cam 15 means for actuating said formed and said spreader, and means for severing the formed springs.
- 10 10. In a machine for the manufacture of springs, the combination of a mandrel, 25 means for continuously feeding the material to said mandrel, a former adapted to coil said material about said mandrel, said former being movable away from and toward said mandrel to vary the diameter of the coils, a spreader adapted to be moved in parallelism with said mandrel to spread the coils as they are formed, and a removably mounted unit cam means for operating said former and said spreader.
- 35 11. In a machine for the manufacture of springs, the combination of a mandrel, means for continuously feeding the material to the mandrel a former adapted to coil the material about the mandrel, said former being movable toward and away from said mandrel to vary the diameter of the coils being formed, a spreader adapted to be moved parallel with said mandrel to spread the coils as they are formed, a rotary shaft, and 40 a removably mounted unit cam means mounted on said shaft to operate both said former and said spreader.
- 50 12. In combination with a machine for manufacturing springs provided with a mandrel, means for coiling the material about the mandrel, means for severing the completed springs, and means for feeding the material consisting of a pair of continuous chains moving in a vertical plane 55 provided with gripping surfaces between which the material is fed to the mandrel.
- 60 13. In combination with a machine for manufacturing springs and provided with means for forming and severing the springs, means for feeding the material consisting of a pair of driven chains provided with parallel flights and having interlacing material gripping means for engaging the material to be fed.
- 65 14. In combination with a machine for manufacturing springs and provided with means for forming and severing the springs, means for feeding the material consisting of a pair of driven chains moving in vertical planes having parallel flights adapted to 70 grip the material to be fed between them.
15. In combination with a machine for manufacturing springs and provided with means for forming and severing the springs, means for feeding the material consisting of a pair of driven chains provided with parallel flights and interlacing material gripping means and means for varying the distance between said flights to adjust the feed to materials of various cross-sections. 75
16. In combination with a machine for manufacturing springs and provided with means for forming and severing the springs, means for feeding the material consisting of a pair of driven chains composed of pivotally connected members provided with interlacing material-gripping projections, said chains having parallel flights adapted to grip the material between them. 80
17. In combination with a machine for manufacturing springs and provided with means for forming and severing the springs, means for feeding the material consisting of a pair of driven chains composed of pivotally connected members provided with material-gripping projections, said chains having parallel flights adapted to grip the material between them, and means for varying the distance between said flights to adjust the feed to materials of various cross-sections. 85
18. In combination with a machine for manufacturing springs and provided with means for forming and severing the springs, means for feeding the material consisting of a pair of chain supporting plates disposed in the same plane, and a pair of driven chains running on the perimeters of said plates and adapted to grip the material between them. 90
19. In combination with a machine for manufacturing springs and provided with means for forming and severing the springs, means for feeding the material consisting of a pair of chain-supporting plates disposed in the same plane, a pair of driven chains running on the perimeters of said plates and adapted to grip the material between them, and means for varying the distance between said plates whereby the feed may be accommodated to materials of various cross-sections. 95
20. In combination with a machine for manufacturing springs and provided with means for forming and severing the springs, means for feeding the material consisting of a pair of chain-supporting plates disposed in the same plane, said plates being provided with continuous sunken perimetral tracks, a pair of driven continuous chains mounted on the perimeters of said plates, and anti- 100
- 110
- 115
- 120
- 125
- 130

friction members mounted in said tracks and supporting said chains.

21. In combination with a machine for manufacturing springs and provided with 5 means for forming and severing the springs, means for feeding the material consisting of a pair of chain-supporting plates disposed in the same plane, said plates being provided with continuous sunken perimetral 10 tracks, a pair of driven continuous chains

mounted on the perimeters of said plates, antifriction members mounted in said tracks and supporting said chains, and means for varying the distance between said plates whereby the feed may be accommodated to 15 materials of various cross-sections.

Signed at Pittsburgh, Pa., this 4th day of August, 1921.

WILLIAM H. BLEUEL.
